UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

AUTOMATIC TRAIN-CONTROL SYSTEM

Original application filed May 18, 1921, Serial No. 470,592. Divided and this application filed February 25, 1927. Serial No. 170,846.

This invention relates to automatic train control systems for railroads, and more particularly to the car equipment of such systems, and is a division of application No. 470,592 filed May 18, 1921.

When a system of automatic train control is applied to a train, there is a natural tendency for the engineer to rely upon this system. If the engineer has confidence in the proper performance of the automatic apparatus, he may perhaps be more lax in his observance of the usual block signals, since he will feel that the automatic devices will in some way give a special warning or apply the brakes automatically in case of danger. It is considered objectionable, however, to take away the vigilance of the engineer, because modern block signal systems are very reliable and efficient, and engineers as a rule are highly trained, experienced and careful operators, so that if the engineer becomes negligent in observing the signal indications or in acting upon them, there is sacrificed a large proportion of the safety of train operation at present obtained by the signal system and the care with which the engineers ordinarily observe and obey the signals. It is evident that the ultimate safety of the train is increased if the automatic train control system is supplementary to the block signal system and the vigilance of the engineer, rather than as a substitute therefor; and if the engineer can be encouraged or forced to observe and act upon the indications of the trackway signals, a serious accident can result only when signal system, the engineer, and the train control apparatus all fail at the same time.

With these considerations in mind, one object of the present invention is to provide a system of automatic train control in which a suitable penalty is automatically enforced if the engineer fails to observe a caution or stop signal, and fails to take some appropriate action in recognition of such unfavorable signal indication. If the engineer observes this indication and acts accordingly, the penalty will not be enforced; and the engineer is thus encouraged to observe and act upon the signal indications. According to the

present invention the penalty in question consists in causing an automatic brake application, or in imposing some suitable form of control, which persists until a reset device is manually operated. This reset device is preferably made accessible only from the ground or is arranged in some other way so that it can not be used without great trouble and annoyance, and is also protected so that it can not be maliciously fastened down, or manipulated in such a way as to avoid the penalty and defeat the purpose of the invention.

This invention is in the nature of an improvement upon the system disclosed and claimed in the application of W. K. Howe, Ser. No. 47,110, filed July 30, 1925; and the patent to Howe No. 1,551,515 dated August 25, 1925.

In the accompanying drawings;

Fig. 1 is a diagrammatic view of one arrangement of trackway circuits applicable to the present invention;

Fig. 2 is a diagrammatic view of a car equipment, the parts and circuits being shown more particularly with the object of making the functions and mode of operation easy to understand, than with the idea of showing the precise construction and arrangement of parts preferably employed in practice;

Figs. 3 to 5 inclusive, illustrate modified wiring arrangements and constructions of the car equipment.

Referring to Fig. 1, the track rails 1 of the railroad track are divided by insulated joints 2 into blocks in the usual way, one block N with the adjacent ends of two other blocks M and O being shown. The parts and circuits associated with the several blocks are the same, and for convenience these will be given like reference characters with distinctive exponents. Each block is provided with the well-known normally closed track circuit commonly used in block signal systems, comprising a track battery 3 and a track relay 4. The usual trackway fixed signals S are illustrated conventionally, and since they may take various forms, such as semaphore signals or color light signals, and may be controlled in any of the well-known ways, no

attempt has been made to illustrate their control circuits and devices, it being understood that these signals will give the usual clear, caution, and stop indications and will be 5 obeyed in accordance with the rules in force on the particular railroad.

In the particular embodiment of the invention illustrated, it is assumed that the transmission or communication of the desired controlling impulses or influences from the trackway to the moving trains for governing the automatic apparatus thereon in accordance with traffic conditions, is accomplished inductively, that is, through an intervening air gap. While this inductive type of impulse transmitting means may take any one of various well-known forms, there is illustrated an arrangement comprising a track element T.

The track element T comprises in general a U-shaped yoke or core 5 of magnetic material, with coils 6 thereon. The coils 6 are wound and connected in series in such a way that the electro-motive-forces generated in the respective coils by flux passing through the yoke 5 are cumulative or additive. These track elements T may be located and controlled in various ways, dependent upon traffic conditions ahead, but in the particular arrangement shown in Fig. 1, a track element T is located at the entrance to each block, a short distance in the rear of the insulated joints 2, the normal direction of traffic being from left to right, as indicated by the arrow. The coils 6 of this track element T are connected in series in a normally closed circuit of low resistance, including the front contact of a line relay D. The energizing circuit for the line relay D includes a front contact 30 of the track relay 4 of the corresponding block, and a front contact of the track relay 4 of the next block in advance. Thus, the coils 6 of the track element T at the entrance to a given block are in a closed circuit under clear traffic conditions, but are open-circuited under caution or stop conditions, that is, when the corresponding block or the next block in advance is occupied. These track elements T may be located crosswise of the track between the track rails as shown, or lengthwise, between or outside of either track rail, and in other ways, provided the car element is disposed accordingly.

The car element Y, see Fig. 2, comprises a similar U-shaped core or yoke 7 of magnetic material and is supported in some suitable manner from the frame of the locomotive or other vehicle, so as to pass directly over the track element T. The air gap between the pole pieces of the track element T and the car element Y is preferably made as short as equipment and roadway clearances will permit. On one leg of the yoke 7 is a coil 8, conveniently termed the primary coil, and

on the other leg of said yoke is another coil 9, conveniently termed the secondary coil.

In connection with the car element Y, there is preferably employed an electron amplifying relay of the thermionic or vacuum bulb type, commonly known as an audion, and which will be referred to by that name as a matter of convenience. This audion, being well-known in the art, is illustrated conventionally, and comprises a filament F, a grid 70 G and a plate P.

The audion controls a car relay R. The features of construction of this relay R, adapting it for use in a train control system of the type shown forms no part of the present invention, and this relay is shown conventionally.

The train control apparatus, which acts to apply the brakes or in some other way govern the train with safety, may take various forms, and since its particular construction forms no part of the present invention, this apparatus has been illustrated conventionally as a device K. This device, shown in the form of an electro-pneumatic valve, may act to vent the 80 train pipe and apply the brakes directly, or govern the operation of some other form of speed regulating or brake controlling mechanism. This device K is normally energized, and is set into operation when de-energized.

In connection with certain forms of the invention, as in Fig. 3 it is necessary to provide the device K with contacts which are broken when said device is de-energized. In the conventional construction illustrated, the core or plunger of the device K carries an insulated disc 10 which engages suitable fixed contacts (shown conventionally as arrows) and thus completes a circuit through said contacts when the device K is energized. When the device K is de-energized, its core or plunger is moved by a spring, air pressure or the like, to move the disc 10 out of engagement with its cooperating fixed contacts, thereby breaking the circuit through said contacts.

The reset switch or button Q is shown conventionally as spring plate or key 11 which normally engages a fixed contact and can be moved from engagement therewith against another contact. This reset switch Q is in practice enclosed in a suitable protecting casing, which may be sealed or locked, or placed so as to be accessible only from the ground, or in some other way arranged so that it can not be operated by the engineer without bringing the train to a stop, or without a great inconvenience, or without calling in the assistance of someone else, the purpose being to make the operation of this reset switch Q so objectionable to the engineer that he will voluntarily observe and obey the signals to avoid the necessity of such operation.

The hold-off switch or device H is arranged in the cab in a convenient position to be op- 125 130

erated by the engineer. The function of this hold-off device H is to close certain contacts, when it is operated by the engineer; and to prevent its improper manipulation, there is provided associated mechanism which prevents the device being held closed or fastened down. A hold-off device of this character is disclosed in a generic form in the Howe application above mentioned, and it is to be understood that no claim is made here to the generic form of the invention disclosed in the said application.

The circuit connections between the audion, the relay R , and the control device K are subject to considerable modification in practice, but since any form of connections suitable for causing operation of the relay R when the car passes an active track element, is applicable to the present invention, only one typical arrangement has been illustrated. The filament F of the audion is heated by the battery A . The grid G is connected in circuit with the secondary coil 9 and the battery C by wires 38 and 39 , so that electro-motive-forces induced in the secondary coil will vary the grid potential. The plate P is connected in circuit with the relay R , a front contact thereof, and the batteries B and C . Referring to Fig. 2 this plate circuit may be conveniently traced as follows:—

commencing at the positive terminal of battery B , wires 40 and 42 , front contact 43 of relay R , wires 44 and 45 , relay R , and wire 46 to plate P .

The primary coil 8 is normally energized from batteries B and C through the train control device K and the front contact 43 of the relay R , this circuit being traced as follows:—commencing at battery B , wires 40 and 42 , front contact 43 of relay R , wires 44 and 47 , reset switch 11 and its closed contact, wire 48 , device K , wire 49 , normally closed contacts 25 — 26 primary coil 8 , and wire 51 to the battery C .

Operation.—The battery C normally produces a positive potential upon the grid G with respect to the average potential of the filament F , and thus permits current to flow in the plate circuit and maintain relay R energized. The current through the primary coil 8 produces a magneto-motive-force tending to send flux through the car yoke 7 , this flux passing in part through the legs of said yoke and in part through leakage paths. The yoke 7 may be said to constitute a partial magnetic circuit with an air gap of relatively high reluctance.

Assume that the car passes over a track element T having its coils 6 open circuited, corresponding to dangerous traffic conditions ahead, that is, when a stopping impulse should be transmitted. The track element in this condition presents in effect a magnetic loop for the yoke 7 on the passing car, and acts to complete the partial magnetic circuit

on the car and change its reluctance, the reluctance decreasing from a normal to a minimum, and then back to normal, as the car approaches and recedes from the track element. This change in reluctance varies the flux passing through the secondary coil 9 , thereby inducing an electro-motive-force in said coil, first in one direction and then in the other. One half of this wave of induced E. M. F. in the secondary coil 9 , either the first or the second half depending upon the connections, opposes the voltage of the battery C and reduces the potential on the grid G . The normal potential on the grid G being thus decreased, the current flowing in the plate circuit through the relay R is likewise decreased, and the parts are so proportioned and adjusted that the current in the relay R is reduced in this way below the amount required to hold its front contact 43 closed. When the front contact 43 opens, the train control device K is de-energized, and the circuit through relay R is also broken at its contact 43 , with the result that said relay can not again pick-up when the grid potential again becomes normal.

Suppose that the coils 6 of the track element T are included in a closed circuit of low resistance, corresponding to clear traffic conditions. When the car element Y passes over a track element in this clear or inactive condition, the relay R is not operated, because the coils 6 on the track element oppose or choke back the passage of flux through the yoke 5 due to the counter-electro-motive-forces induced in said coils, with the result that there is little change in flux through the secondary coil 9 and the relay is not operated.

The operation so far described is that which is characteristic of the type of system illustrated, this particular system being merely illustrative of one suitable for the application of the present invention, and being disclosed and claimed in other applications. Arrangements to prevent improper operation of the car equipment by track rails or other masses of iron along the track, and various other expedients that may be necessary or desirable in a complete system, are not material to the present invention, and being fully disclosed in other applications, are not herein illustrated. Further, the operation so far described does not take into consideration the action of the hold-off device H , the reset switch Q , and associated parts constituting the subject-matter of the present invention.

As previously explained, the purpose of the present invention is to provide an arrangement for enforcing vigilance on the part of the engineer in observing and acting upon the indications of the fixed signals. The engineer is supposed to watch out for the various fixed signals S , and if one of these signals indicates caution, it is intended that he should operate the hold-off device H while passing

- the corresponding track element T, this act being in recognition of the cautionary indication of the signal and an acknowledgment that there is another train a short distance ahead. It is assumed that if the engineer makes such a positive movement, he fully appreciates the existence of danger and may be relied upon to slow down the train or take such action as is necessary to avoid a collision.
- Consequently, if the engineer is alert and operates the hold-off device at the proper time in recognition of a caution signal, it is unnecessary to take the control of the train out of his hands or apply the brakes at once; and the preferable arrangement of circuits is such that timely operation of the hold-off device H prevents, in some of the ways hereinafter described, the effective action of the track element upon the train control device K.
- If the engineer is not alert, however, and due to negligence or any other cause fails to see or read correctly the signal indications, he will not operate the hold-off device at the proper time, and then the train control apparatus K will be automatically set into operation as the train passes over the active track element, thereby slowing down the train and avoiding a collision. Further, the construction is such that the control exerted by said apparatus upon the train will be maintained until the reset switch Q is operated. If this reset switch Q is accessible only from the ground, so that the train must be stopped before it can be actuated, or if operation of this switch is made difficult or objectionable in some other way, the engineer will naturally prefer to operate the hold-off device H in recognition of each caution signal, rather than be subjected to the special trouble, annoyance, or publicity of actuating the reset switch Q. It may be noted here that the penalty, being self-inflicted, so to speak, and concurrent with the default, will naturally have more influence than any subsequent discipline, although it is evident that a recorder or similar device may be used in conjunction with the system shown and described to provide a check upon the way in which the engineer performs his duties.
- Referring now to the specific arrangement of circuits and devices for preventing effective action of an active track element upon the train control device K when the hold-off device H is properly operated, and for imposing a penalty when such device is not properly operated, Fig. 2 shows an arrangement in which the timely and proper operation of the hold-off device H, prevents dropping of the relay R. This is done by providing connections, comprising wires 57-58, which cause the secondary coil 9 to be shunted when the contacts 16-18 of the hold-off device are closed. This maintains the potential on the grid G, and prevents de-energization of relay R, irrespective of the voltage changes in the secondary coil. To check the hold-off device H against improper operation, its normally closed contacts 25-26 may be included in the energizing circuit of the apparatus K as shown in Figs. 2 and 3, or in the stick circuit for the relay R as shown in Fig. 5. The cam 22 is in practice biased in a clockwise direction by a force less than that exerted by the spring 15, so that this cam 22 is held in the normal position shown by the handle 12 engaging the pin 23. If however, the handle 12 is depressed by the engineer, the cam 22 is rotated in a clockwise direction at a restricted rate as determined by suitable time controlled mechanism, more specifically described in the parent application.
- In the modification shown in Fig. 3, provision is made for imposing a more severe and immediate penalty for misuse of the hold-off device than in the embodiment of the invention shown in Fig. 2. Referring to Fig. 2, it will be noted that if the engineer holds or fastens down the handle 12 too long and the contacts 25-26 open, because the cam 22 will have rotated to a position where it allows opening of contacts 25-26, the train control device K is de-energized; but since the engineer may re-energize the device K and proceed by merely restoring the handle 12 to the normal position shown, there is no particular penalty imposed for such misuse of the hold-off device. It is noted here that the arrangement of circuits shown in Fig. 2 may under certain circumstances act to impose a penalty for the misuse of the hold-off device, that is, require operation of the reset switch Q. When the contacts 25-26 open, they break the circuit through the primary coil 8, as well as through the train control device K, resulting in a collapse of the flux produced by said primary coil, and also of that flux normally passing through the secondary coil 9. Such collapse or change in flux through the secondary coil 9 may reduce the grid potential and cause dropping of the relay R, depending upon the size and proportion of the parts, the strength of the currents in the respective circuits, and the manner of connection. In this way the relay R is dropped when the handle 12 is held down too long, and consequently the reset switch Q must be operated before the train control device K can be restored and the train proceed.
- In the modification shown in Fig. 3, however, if the handle 12 is held down too long, and the train control device K is operated, the train cannot be relieved of the control enforced by said device K until after a special resetting manipulation has been performed. Referring to Fig. 3, the normally closed energizing circuit for the train control device K is taken through its own contacts 10, said energizing circuit, commencing at the reset switch Q, being traced along wires 48 and 59,

through contacts 10, wires 60 and 61, device K, wire 49, and thence through the contacts 25-26 and primary coil 8 to the battery. When the contacts 25-26 open because the handle 12 is held down too long, and the device K is consequently de-energized for reasons already given, the contacts 10 operated by the device K (conveniently termed the stick contacts) make another break in the normal energizing circuit for said device, so that it can not be re-energized by merely restoring the handle 12, and must be re-energized by another circuit.

While the restoration of the train control device K may be accomplished in various ways, in the arrangement of circuits shown in Fig. 3, two push buttons or hand switches 62-62¹ are provided at different places on the train, one for operation by the engineer, and the other by the fireman, conductor, or other person. These push buttons 62-62¹ which have been shown conventionally, may be located so that they are accessible only from the ground, or may be housed and locked in some suitable way, or otherwise protected, so that they can not be operated without objectionable trouble and annoyance. It is noted here that instead of two push buttons 62-62¹ operated at the same time, only one push button may be used if desired.

Each of the push buttons 62 and 62¹ has a normally opened contact 63 and a normally closed contact 64, the first being closed and the other opened simultaneously when the push button is actuated. The normally closed contacts 64-64¹ are included in the branch or shunt circuit for the secondary coil 9 in series with the contacts 16-18, so that if either of these push buttons is held or fastened down, the shunt circuit for the secondary coil can not be established by operating the hold-off device H. In other words, if either of the push buttons 62-62¹ is fastened down, the hold-off device is made useless. The normally opened contacts 63-63¹ of the push buttons are in series in a shunt circuit around the stick contacts 10 of the train control device K, said shunt circuit comprising wires 60 and 67, contact 63, wire 68, contact 63¹, and wires 69 and 59.

The modification shown in Fig. 3 operates in the following manner. Assuming that the engineer holds down the handle 12 too long allowing contacts 25-26 to open for reasons already given, and the train control device K is rendered active, then in order to restore this train control device, the engineer must first restore relay R by depressing reset push button 11, must then return the handle 12 to the normal position shown so as to close contacts 25-26, and then the push buttons 62-62¹ must be simultaneously actuated by the engineer and the fireman. This manipulation establishes an energizing circuit for the device K through relay contact 43, reset switch Q,

through switches 63-63¹, and the contacts 25-26. As soon as the train control device K is energized, its contacts 10 close, and the push buttons 62-62¹ may be released. In this way, the engineer is penalized for negligent or malicious misuse of the hold-off device H, the severity of this penalty depending upon the annoyance and difficulty incident to the operation of the push buttons 62-62¹. One advantage of having two push buttons that have to be operated simultaneously is that the engineer must then call in the fireman or conductor to assist in getting the train control device restored and the train under way again, thus giving publicity to the engineer's default. It will be evident that the push buttons 62-62¹ can not be maliciously fastened down, since the usefulness of the hold-off device H is thereby destroyed, and an operation of the train control device K will occur at the next caution signal, requiring manipulation of the reset switch Q as well as the push buttons 62-62¹. Also, this modified arrangement shown in Fig. 3 imposes a greater penalty for failure to make timely operation of the hold-off device H, since the push buttons 62-62¹ must be actuated in addition to the reset switch Q, thereby occasioning still more trouble and annoyance.

While the provision of contacts 10 on the train control device K in its own energizing circuit, together with the push buttons 62-62¹, has been shown in Fig. 3 in connection with the embodiment of the invention in which the effective action of a cautionary impulse is neutralized by the hold-off device H by virtue of establishing a shunt for the secondary coil 9, the same arrangement may be used in connection with the embodiment of the invention shown in Fig. 2 and a special penalty provided in this way for misuse of the hold-off device. The adaptations of the circuit arrangement shown in Fig. 3 to the form of the invention shown in Fig. 2 will be obvious and have not been illustrated separately.

Fig. 4 shows a modified arrangement of the parts and circuits constituting the invention, in which the operation of the hold-off device H prevents effective action of the cautionary impulse by maintaining the control relay R energized. In this modified arrangement, when the handle 12 is moved down and contacts 16-18 are closed, the relay R may be maintained energized independently of the decrease in current between the plate and filament of the audion by an auxiliary energizing circuit as follows: commencing at an intermediate tap of the battery B, wire 70, adjustable resistance 71, wire 72, contacts 16-18, wire 73, and relay R, wires 45 and 44, front contact 43, wires 42 and 40 to the end tap of the battery B. The voltage of the section of the battery B included in this circuit,

together with the resistance 71, is proportioned with regard to the resistance of the audion between the plate and filament, so that the current supplied to the relay R corresponds substantially with its normal working current when governed by the audion.

The modified circuit arrangement shown in Fig. 4 has the same general characteristics of operation that have been described. As the engineer approaches a caution signal, he may press down the lever 12 and close contacts 16-18, thereby preventing the relay R from dropping as the car element Y passes over the track element T in the active stopping condition. If the engineer does not make proper and timely operation of the hold-off device H, the relay R is de-energized, and the train control device K set into operation in the regular way. After the relay once becomes de-energized, and its front contact 43 opens, the reset switch Q must be actuated before the train control device K can be re-energized.

In the arrangement shown in Fig. 4 the engineer is prevented from misusing the hold-off device H by reason of the fact that this will set the train control device K into operation.

As shown in the modified form of Fig. 5, instead of protecting the hold-off devices H against improper manipulation in the way shown in Fig. 4, its normally closed contacts 25-26 may be included in the stick circuit of the relay R (see Fig. 5), whereby, if the handle 12 is held down too long, the device K is directly de-energized by opening of contacts 25-26 and is further de-energized by opening of contact 43 due to the de-energization of relay R, which relay R remains de-energized until reset push button 11 has been depressed.

Having thus shown and described my invention, it is to be understood that my invention is not limited to the specific arrangements shown and described.

What I claim is:—

1. In an automatic train control system, an electromagnetic brake control device on a vehicle, a relay governing said device, traffic controlled means of the induction type for controlling the relay through an intervening air gap, and manually operable means adapted only if operated in time to prevent operation of the relay and having a limited time of effective operation.

2. An automatic train control system comprising, a brake applying means acting on the usual air brake system, automatically actuated control means for governing said brake applying means, means on the vehicle for preventing the actuation of said control means and effective only if actuated before action of said control means has been initiated, means accessible only from the ground for resetting said brake applying means to

normal, and means for protecting said manually operable means against misuse including means for effecting a brake application so long as said manually operable means is not returned to its normal position.

3. In an automatic train control system for railroads having tracks divided into blocks and equipped with track circuits and trackway block signals, the combination with an inductive track impulse device near each block entrance having a control circuit and assuming its active impulse transmitting condition if the control circuit is open, means for opening said control circuit for each track device if the corresponding signal indicates caution or stop, of car-carried equipment comprising, a brake setting device normally energized electrically and acting when deenergized to cause an automatic application of the brakes, an energizing circuit for said device, a normally energized stick relay acting when de-energized to break said energizing circuit, a stick circuit for said relay including a normally closed front contact thereof, impulse receiving means cooperating with said track impulse device and acting during the passage of the car past a track device in its active stopping condition to reduce temporarily the flow of current in said stick circuit and tend to cause said relay to release its armature and operate said brake setting appliance, manually operable circuit controlling means conveniently accessible to the operator of the vehicle and acting when in its operated position to prevent de-energization of said stick relay by an active track impulse device, said manually operable means having normally closed contacts included in the energizing circuit for the brake setting appliance and opening automatically after a predetermined time following each operation of the manually operable means, a reset switch accessible only from the ground and having normally open contacts and normally closed contacts, said normally closed contacts of the reset switch being included in said energizing circuit for the brake setting appliance, and said normally open contacts of the reset switch closing a shunt around said front contact of said stick relay and thereby permitting re-energization thereof.

4. In an automatic train control system, the combination with a car-carried stick relay, of impulse transmitting means partly on the car and partly on the track cooperating magnetically without physical contact to reduce the current temporarily in the stick circuit of said relay and tend to cause retraction of the armature of said relay, the armature of said relay when once retracted by the action of said impulse transmitting means remaining in the retracted position until otherwise restored, a normally ener-

- gized electro-pneumatic valve de-energized upon retraction of said armature and acting to produce an automatic brake application, a manually operable acknowledging device conveniently accessible to the operator of the vehicle and acting in the operated position to prevent retraction of the armature of said stick relay if then in its attracted position, said acknowledging device acting automatically to de-energize said electro-magnetic valve and cause an automatic brake application if kept in its operated condition longer than a predetermined interval of time, a reset switch accessible only from the ground and operable to establish a shunt around the stick contacts of said relay and permit attraction of its armature after retraction thereof, said reset switch while in its operated position maintaining said electro-magnetic valve de-energized.
5. In an automatic train control system, car equipment adapted to apply the brakes of the car automatically upon transmission of a stopping influence from the trackway unless the operator of the car performs an anticipatory acknowledging act, comprising, a normally energized stick relay, means included in the stick circuit of said relay and responding to control influences from the trackway and tending to de-energize said relay, a manually operable acknowledging device acting in its operated condition to render said means ineffective and thereby prevent de-energization of said stick relay, a normally inactive brake control device tending to assume its active condition and to cause an automatic brake application, a normally energized circuit for said brake control device opened upon de-energization of said stick relay, time controlled means for independently opening said energizing circuit after a predetermined time interval following each operation of said acknowledging device, said time controlled means being automatically restored to normal when said acknowledging device returns to normal, and reset means manually operable only after the car is stopped to re-energize said stick relay, said reset means opening said energizing circuit for the brake control device while in its operated position.
6. In an automatic train control system of the type described, the combination with a normally energized electro-magnetic valve on a vehicle automatically causing a brake application upon its de-energization, an energizing circuit for said valve, means temporarily influenced from the trackway through an air gap and without physical contact for interrupting said energizing circuit, said means when once operated to break said energizing circuit remaining in that operated condition until manually restored, an acknowledging device on the vehicle conveniently located for manual operation by the engineer and acting 60 when operated to maintain said means inac-
- tive but being incapable of restoring said means once it has assumed its active condition, time controlled means governed by said acknowledging device and acting automatically to apply the brakes if said device is kept in its operated position longer than a predetermined time, and resetting means manually operable only after the vehicle has come to a stop for restoring said means to normal, said resetting means while in the operated position maintaining said valve de-energized.
7. In a train control system, cooperating track and car-carried elements, a device for applying the car brakes when initiated, electrically operated stick controlling means for initiating said device and normally affected by trackway influences to initiate said device, and acknowledging means operable to prevent the said affecting of the controlling means by said trackway influences, said acknowledging means including means automatically operable after a predetermined time interval from operation of the acknowledging means, to cause initiation of said device, and reset means, when operated, initiating said device and closing a pick up circuit for said stick controlling means.
8. Car-carried apparatus for automatic train control systems of the type in which control influences are transmitted upon passage of the vehicle by control points under adverse traffic conditions ahead, comprising a stick relay having a stick contact closed when said relay is energized; a source of energy; a circuit for energizing said relay normally closed and including in series the winding of said stick relay, said stick contact, said source of energy and an impulse device responsive to control influences transmitted from the trackway; said device effecting de-energization of said relay upon passage of the vehicle by a control point under adverse traffic conditions ahead; an electrically operated valve energized by a circuit including a front contact of said relay and acting if de-energized to effect an application of the air brakes of the vehicle; and a manually operable acknowledging switch having normally closed contacts included in the energizing circuit of said valve and normally open contacts which if closed render said impulse receiving device ineffective, said normally closed contacts remaining closed only for a limited period of time after each operation of said switch.
9. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including in series the winding of said stick relay, said stick contact, said source of en-

- ergy and a device responsive to control influences transmitted from the trackway, said device effecting de-energization of said relay upon passage of the vehicle by a control point under adverse traffic conditions ahead; an electrically operated valve energized by a circuit including a front contact of said relay which valve is normally energized and which if de-energized affects an application of the air brakes of the vehicle; and manually operable restoring means accessible only from the ground having normally closed contacts contained in the energizing circuit of said valve and having normally open contacts which if closed shunt the stick contact of said stick relay, said restoring means being constructed so that if operated to its abnormal position the normally open contacts are closed and the normally closed contacts are opened, whereby if said restoring means is left in its operated position the brakes are maintained applied. 70
10. Car-carried apparatus for automatic train control systems of the type in which control influences are transmitted upon passage of the vehicle by control points under adverse traffic conditions ahead comprising, a stick relay having a stick contact closed when said relay is energized; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point under adverse traffic conditions ahead; an electrically operated valve energized by a circuit including a front contact of said relay which valve is normally energized and which if de-energized affects an application of the air brakes of the vehicle; manually operable acknowledging means which if operated shunts an essential portion of said device so as to make this device ineffective; and manually operable restoring means for the relay. 75
11. Car-carried apparatus for automatic train control systems of the type in which control influences are transmitted upon passage of the vehicle by control points under adverse traffic conditions ahead comprising, a stick relay having a stick contact closed when said relay is in its energized position; a source of energy; a circuit for energizing said stick relay including a stick contact, the winding of said relay, said source of energy, and a device responsive to control influences transmitted from the trackway and in response thereto reduces the current flow in said circuit, in series; and an electro-pneumatic valve normally energized by a circuit including a contact on said relay closed when said relay is in its energized condition and a source of energy; and manually operable restoring means accessible only from the ground for restoring said relay and electro-pneumatic valve to normal; said restoring means including normally closed contacts contained in the energizing circuit of the electro-pneumatic valve and normally open contacts which if closed shunt the stick contact of said stick relay, said restoring means being constructed so that if operated to its abnormal position the normally open contacts are closed and the normally closed contacts are opened, whereby said restoring means is protected against being left in its operated position permanently. 80
- In testimony whereof I affix my signature.
CHARLES S. BUSHNELL. 100
12. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 105
13. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 110
14. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 115
15. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 120
16. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 125
17. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 130
18. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 135
19. Car-carried apparatus for automatic train control systems of the type in which control influences are transmitted upon passage of the vehicle by control points under adverse traffic conditions ahead; the combination of a stick relay having a stick contact closed when said relay assumes its energized position; a source of energy; a circuit for energizing said relay normally closed and including the winding of said stick relay, said stick contact, said source of energy and a device responsive to control influences transmitted from the trackway, in series; said device effecting de-energization of said relay upon passage of the vehicle by a control point un- 140
